SPEAR POLE FOR REMOVING PAPER FROM THE ROLLERS OF PAPER-MAKING MACHINES

Application filed November 23, 1929. Serial No. 409,385.

This invention relates to new and useful improvements in spear poles for removing paper from the rollers of paper making machines when the same become clogged.

5 When the rollers of paper making machines become clogged, it is necessary to remove the paper by poles carrying knives. If hard wood poles are used for this purpose, they will frequently tear from the rollers the 10 felt covering which is very expensive to replace.

On the other hand, solid soft wood poles, which will not tear the felt, are not strong enough to remove the paper from the rollers 15 when they become clogged up.

To provide a wood pole which will have sufficient strength to remove paper from the clogged paper-making machine rollers without tearing felt from them is the object of this 20 invention. Such a pole I construct of laminated soft wood such as white pine. By making it three ply, the strength of the pole is doubled and still it is soft enough not to injure the felt on the rollers.

25 In the accompanying drawings illustrating my invention, Figure 1 is a perspective view of my laminated spear pole. Figure 2 is a cross sectional view taken through the same before it is turned. And Figure 3 is a 30 cross sectional view taken through the same after it has been turned to cylindrical form.

Referring to the accompanying drawings for a detailed description of my invention, the numeral 1 designates a soft wood spear 35 pole of suitable length to remove paper from the clogged rollers of a paper making machine by a knife (not shown) fitted thereto. This pole is made up of three laminations 2, 3 and 4 of soft wood such as white pine or 40 basswood. These laminations or strips are rectangular in cross section as shown in Figure 2, with the middle section formed with longitudinal semi-circular grooves to receive tongues 5 projecting longitudinally 45 from the inner surfaces of the sections 3 and 4.

The sections 2, 3 and 4 of the pole are glued together in a suitable press to form the laminated unit shown in Figure 2, after which the structure is turned to cylindrical form in

a lathe. The pole shown in Figures 1 and 3 is the result. It is strong enough to remove paper from the clogged paper making machine rollers without breaking, and will not injure the felt on them during the removal 55 operation.

Having described my invention, I claim:

1. A laminated soft wood spear pole for removing paper from the clogged up rollers of a paper making machine.

2. A spear pole for removing paper from the clogged up rollers of a paper making machine, comprising a plurality of soft wood strips glued together and turned to cylindrical form.

3. A spear pole for removing paper from the clogged up rollers of a paper making machine, comprising three soft wood strips glued together and turned to cylindrical form, and a tongue and groove connection 70 between the middle strip and the outer ones.

In testimony whereof I have hereunto set my hand this 20th day of November, 1929.

RAY B. HULL.
